UNITED STATES PATENT OFFICE.

JOSEPH W. PARKIN, OF PHILADELPHIA, PENNSYLVANIA.

DESIGN FOR A MOTOR-BICYCLE FRAME.

SPECIFICATION forming part of Design No. 34,252, dated March 19, 1901.

Application filed February 5, 1901. Serial No. 46,147. Term of patent 7 years.

To all whom it may concern:

Be it known that I, JOSEPH W. PARKIN, a citizen of the United States, residing at Philadelphia, in the county of Philadelphia and State of Pennsylvania, have invented and produced a new and original Design for a Motor-Bicycle Frame, of which the following is a specification, reference being had to the accompanying drawing, forming part thereof.

The drawing represents a side elevation of a motor-bicycle frame, showing my new design.

As shown in the drawing, the frame comprises the head A, the bar B, the strut C, the bar D, the post E, the bearing F, and the reach G, extending downwardly from the bear-

ing F and then upwardly to the head A, so as to form the curve g, the leading or material feature residing in the form and arrangement of the reach G.

Having described my invention, what I claim as new, and desire to secure by Letters Patent, is—

The design for a motor-bicycle frame, substantially as shown and described.

In testimony whereof I have signed my name to this specification in the presence of two subscribing witnesses.

JOSEPH W. PARKIN.

Witnesses:

WILLIAM R. DARAH,
CHARLES N. BUTLER.
